UNITED STATES PATENT OFFICE.

THOMAS J. WATSON, OF SHORT HILLS, NEW JERSEY, ASSIGNOR TO COMPUTING-TABULATING-RECORDING CO., OF NEW YORK, N. Y., A CORPORATION OF NEW YORK.

TIME RECORDER.

Application filed February 11, 1922. Serial No. 535,786.

To all whom it may concern:

Be it known that I, THOMAS J. WATSON, a citizen of the United States of America, residing at Short Hills, in the county of 5 Essex and State of New Jersey, have invented certain new and useful Improvements in Time Recorders, of which the following is a full, clear, and exact description.

10 This invention relates to certain improvements in cost keeping and elapsed time machines.

In keeping costs, it is frequently desirable to provide individual time recorders which 15 can be assigned one for each workman or one for each job or machine. Such a recorder should preferably provide a printed record of elapsed time which has accrued between two time periods and also it materially simplifies cost keeping if the record 20 can show the money value of the wages or charges which have accrued for the operation. Such money values usually bear a pre-determined relation to the amount of elapsed 25 time which is recorded and usually are a direct multiple thereof. In certain cases this money value may also include an overhead or fixed charge in which case the money value would equal the elapsed time multiplied 30 by a rate and increased by an amount representing overhead or fixed charges.

Since a large number of machines of this sort are provided in each establishment, it is important that their construction be simple and rugged and that the machines also 35 be comparatively inexpensive. Otherwise their extensive use would be prohibitive. Furthermore they must be so arranged as to prevent the making of improper records 40 and preferably their operation should be as fully automatic as possible.

To this end I have devised the present construction and provide a machine which requires merely the depressing of a lever 45 and the manual resetting of the type wheels to zero after a complete record has been taken therefrom. Provision is made for automatically changing the printing point after the initial or "start" record is taken 50 and after the second or "final" record is taken and the machine reset, the printing point is automatically restored to receive a new card in proper position for an initial or start record thereon.

55 Fig. 1 of the drawings shows a side view

of the machine with side covering plate removed to show the interior construction. The section is indicated at 1-1 on Fig. 3.

Fig. 2 is a sectional view taken on line 2-2 of Fig. 3.

Fig. 3 is a top view of the interior mechanism of the machine and is in part a section taken on line 3-3 of Fig. 1.

Fig. 4 is a detail view of the ribbon devices and is taken on line 4-4 of Fig. 1.

Fig. 5 is a detail enlarged view of the handle interlocking mechanism and shows the same parts shown in Fig. 2 in displaced position.

Fig. 6 is a detail sectional view taken on line 6-6 of Fig. 2.

Fig. 7 is a fragmentary view of a card as printed by the machine.

In more detail the machine comprises an enclosing casing 10 of any desired form. 75 Within the casing are suitable frame members 11 which support a through shaft 12 so as to permit rotation thereof. Fixed to this shaft is a wheel 13 preferably carrying upon its periphery a plurality of rows of type 14 and 15. Row 14 is a time row and 15 a value, cost or wage row. Each of the time types has in alignment with it, value, cost or wage types of numerical value equal to the time multiplied by the proper rate. In 80 certain establishments where it is desired to add overhead to the costs, this amount may be included in the cost type values. The general arrangement of the printing wheel 85 may be widely varied to meet any desired cost keeping system, it being only essential that each time type have in alignment therewith a corresponding value type element if such values are to be recorded.

To advance the type wheel a suitable 90 spring 17 is provided which is preferably of the clock spring type having one end fixed to the type wheel and the other to the frame (see Fig. 6). Fixed to one side of 100 the type carrying wheel is an aligning wheel 18 having ratchet teeth upon its periphery. The aligning wheel carries a pawl 19 which engages a ratchet wheel 20. The latter wheel together with an escapement wheel 21 are 105 both fastened to a suitable sleeve 22 which is rotatably mounted upon shaft 12 (see Fig. 3.) Cooperating with wheel 21 is an escapement device 23 of well known type which is periodically actuated by magnets 110 24 to release the escapement wheel and to

permit it to advance step by step. Magnet 24 is connected to the usual time clock controlled circuit and receives electric current impulses at predetermined time periods. 5 The release of the escapement wheels permits the type wheel 13 to advance under the power of spring 17. The pawl device 19 permits the resetting of the type wheels to zero position and the restoring of power 10 in the spring.

A card receiver 25 of the usual type is mounted in the casing at a proper point to position a card adjacent the printing point of the type wheels. The receiver is provided 15 with an adjustable card abutment 26 upon the end of a bell crank lever 27 which serves to control the depth to which the card can be inserted. The main operating handle 28 is loosely mounted upon a shaft 29 and provided 20 with a hook pawl 30 adapted under certain conditions to engage a block 31 fixed to shaft 29 and to retract hammer 32 against the tension of a spring 33 (Fig. 1). By depressing the handle fully, the hook 25 pawl 30 trips off block 31 and allows the spring 33 to throw the hammer against the type ribbon 34 and imprint a record from the type upon the record card. The usual ribbon feeding and reversing devices 35 are 30 provided which, being of conventional type, need not be described in detail.

The first operation on this machine consists in setting the type wheels back to zero. A resetting knob 36 carried upon the 35 end of shaft 12 is provided for this purpose and this knob is rotated clockwise until a movable stop 37 comes into contact with fixed stop 38. During this resetting operation type wheel 13 is turned to bring the 40 zeros of the time and value type to the printing point, aligning wheel 18 is rotated with the type wheels and the escapement wheel 22 and pawl wheel 20 remain stationary, pawl 19 clicking idly over the teeth of 45 ratchet wheel 20. The parts are now in the position shown in Fig. 2.

A card is inserted in the card receiver and descends to a position determined by the card abutment 26. Handle 28 is then depressed. Upon the initial downward movement of this handle, a linkage 39, 40 connected to the hammer rocks an aligning pawl 41 into engagement with aligning ratchet wheel 18 and aligns the type at the printing point. This operation is first completed and the hammer 32 is then impelled against the type to print zeros upon card 42 as shown at 43, Fig. 7. During the aforesaid first printing operation the card abutment lever 44 is held in lower position by means of a stop 45 carried by the aligning wheel 18 (see Fig. 2). This aligning wheel will have previously been restored together with the type wheels by the rotation of resetting knob 36. The current pulses from the master clock

now periodically actuate magnet 24 and the escapement wheel is released step by step, permitting a similar advance of the type and alignment wheels under the power of spring 17. After the first time impulse, stop 44 will move from under the projection on the card abutment lever 27 and spring 45 will swing this lever, counterclockwise against a stop (see Fig. 5). The parts are now ready for the taking of a "second" 75 record of elapsed time and cost. This may be done at any time. The operator inserts the card in the receiver, the card abutment having now been shifted upwardly, the second imprint will be at a different position 80 upon the record card. Printing is now carried out as before and the time and value imprints will be made upon the record card as shown at 46 (Fig. 7).

The card record is now complete, and prior to the next operation the type wheels must be reset to zero. Means are provided for preventing an effective printing operation until the type wheel is entirely reset to zero. The operator therefore, after the second printing operation, must turn the resetting knob and turn it completely. This operation restores the card abutment lever to initial position. The mechanism for these purposes will now be described.

A spring lever 47 is provided pivoted upon a suitable frame member and engaging at its upper end a pin 48 upon the card abutment lever 27. The lower end of this lever 47 overlies the end of the hook pawl 30 during the first printing operation and during the depression of the handle 28 upon the second printing operation. After entirely depressing the handle on the second operation, lever 27 having been raised, lever 47 will swing in the path of the nose of the hook pawl 30 and prevent its swinging into a position to cooperate with block 31 upon the next downward operating stroke of handle 28 (see Fig. 5). Thereafter any manipulation of the handle will be ineffective upon the hammer. The foregoing condition maintains until the type wheels are reset to zero, when projection 44 will cam downwardly upon the card abutment lever 27, 115 restoring pivoted lever 47 to the position shown in Fig. 2 and setting the card abutment for zero printing upon the next "first" operation. The handle may now be depressed as before.

I claim—

1. A time recorder comprising a time controlled type wheel, a record support, means for taking a printed record from said wheel, means controlled by the advance of said wheel from its initial position for shifting said record support relatively to said wheel, and means for resetting said wheel to zero and restoring said record support to its initial position.

2. In a time recorder, in combination, a time controlled type wheel, a record support, means operable upon the movement of said wheel for shifting said support, means for taking off successive start and finish printed records from said wheel, means for resetting the wheel to zero, and means for preventing the taking of a start record until the wheel has been reset.
- 10 3. A time recorder comprising in combination, a time controlled type wheel, means for taking records therefrom at successive positions upon a record sheet, means for resetting said wheel to zero, and means for preventing the taking of a start record until the wheel has been reset.
- 15 4. A time recorder comprising a time controlled type wheel, a record support, means for shifting said support relatively to said 20 wheels to position a record to receive successive imprints at different positions thereon, means for resetting said wheel to zero, and means operable upon the resetting of the wheel to zero for shifting the record 25 support to its first record receiving position.
5. A time recorder comprising a time and value type wheel, means for positioning the same in accordance with elapsed time, 30 means for resetting the wheel to zero to receive a new time record, means for taking a printed record of time and value from said wheel, and means for preventing the taking of a record from the wheel after the 35 first elapsed time record has been imprinted upon a record.
6. A time recorder comprising a time and value type wheel, means for initially resetting the same to zero, means for taking an 40 initial record therefrom, means for advancing said wheels in accordance with a time factor, means for thereafter taking a second "finish" record from said wheels, and means for thereafter preventing the taking of an 45 other record from said wheel until the resetting means has been operated to restore the wheel to zero position.
7. A time recorder comprising in combination, a wheel carrying related time 50 and value type, time controlled means for advancing said wheel, means for taking a record of elapsed time and corresponding value from said type, and means for resetting said wheel to zero and for preventing the taking of a record until said wheel 55 is reset.
8. In a time recorder, in combination with a time controlled type wheel, a record support, means for taking a printed record 60 from said wheel, means controlled directly by the advance of said wheel from initial position and independently of the record for shifting said support from initial position immediately after a "start" record is taken
- to permit the taking of a "finish" record, 65 and manually operable means for restoring the record support to initial position.
9. A time recorder including in combination, a time-controlled type wheel, a record card receiver, means for taking records from 70 the said wheel, means called into action upon the initial advance of the time wheel for shifting the card receiver to position the card for receiving a further record, and means operable upon the taking of a 75 second record for preventing the taking of further records.
10. A time recorder including in combination, a time-controlled type wheel, a record card receiver, means for taking 80 initial and second records from the said wheel, means for shifting the card receiver to position the card for receiving a second record, means operable upon the taking of a second record for preventing the taking 85 of further records, means for restoring the card receiver to initial position, means for resetting the type wheel to zero, and means for releasing the record taking means whereupon a new start record may be 90 taken.
11. A time recorder including in combination, a time-controlled type wheel, means for taking zero and elapsed time records from the said wheel, and means operable upon the taking of an elapsed time record for preventing the taking of further records until the machine is reset for a start or zero record. 95
12. A time recorder including in combination, a time-controlled type wheel, a record card receiver, means for taking first and second records from the said wheel, means for shifting the card receiver so that the record card may receive successive 100 time imprints, means operable upon the taking of a second record for preventing the taking of further records, and means for restoring the card receiver to initial position and for releasing the record taking 105 means whereupon a new first record may be taken.
13. A time recorder including in combination, a time-controlled type wheel, a record support, means for taking start and finish records from the said wheel, means for shifting the card support to position the start and finish record at successive points on the record, means operable upon the taking of a second record for preventing the 110 taking of further records, and means for restoring the card receiver to initial position and for resetting the type wheel to zero. 115
- In testimony whereof I hereunto affix my 120 signature.

THOMAS J. WATSON.
